AUTOMATIC TELECOMMUNICATION
EXCHANGE SYSTEM

George Clifford Hartley, London, England, assignor to Standard Telephones and Cables Limited, London, England, a British company

Application August 16, 1943, Serial No. 498,771
In Great Britain October 22, 1942

7 Claims. (Cl. 179—27)

This invention relates to automatic telecommunication exchange systems and more particularly to arrangements for receiving direct current impulses.

The arrangements according to the present invention are intended for signalling by direct current over comparatively long lines.

According to the present invention a telephone system in which connections are set up automatically by means of impulses over a junction line comprises a polarised telegraph relay for receiving said impulses, said relay being biased by means of a current flowing in one winding thereof.

The biasing current is preferably adjusted in accordance with the length of line over which the impulses are to be sent.

Preferably means is provided by short circuiting part of the resistance connected across the incoming end of said junction line in order to send a supervisory signal to the outgoing end, a marginal relay being connected at the outgoing end to respond thereto.

Preferably also means is provided for automatically reducing the value of the biasing current for the telegraph relay after the response to the first impulse so that the first impulse is lengthened to correct for artificial shortening of the impulse which is otherwise liable to occur.

Preferably also in a repeater for the impulses at the incoming end of the line the impulse responding relay is separated from the contacts repeating the impulses by means of a high pass filter which prevents surges due to the repeating contacts from interfering with the operation of the sensitive telegraph relay, without substantially attenuating speech currents.

The invention will be better understood from the following description of one embodiment thereof taken in conjunction with the accompanying drawing which shows circuits at the outgoing and incoming ends of a junction J. At the outgoing end the junction circuits are connected to a jack adapted to be connected to an operator's cord circuit. Impulses from the operator's dial are repeated to the junction J by contacts h_1 of relay HS, the manner of sending the impulses over the junction J being similar to that described in U. S. Patent No. 2,207,537, so that the growth and decay curves of the current over the junction J are symmetrical. Instead, however, of sending an impulse over the junction by removing a short circuit on the junction as in specification No. 176,804, impulses are sent by placing a short circuit on the junction though either method of sending the impulses could be used. These impulses instead of being received over a transformer as described in the above mentioned patent, are received over one winding of a polarised telegraph relay T which is connected in series with a high resistance R_3 and a retard coil IL

across the junction J. The polarised telegraph relay is biased by means of current in its other (lefthand) winding, this winding being connected in series with resistances R_1 and R_2 the values of which are adjusted in accordance with the resistance of the junction J so that the response on different junctions is the same, the biasing current being adjusted to be about half the current over the junction. It will be understood that the resistance of the junction J will depend upon the kind of junction line as well as upon its length, being for example less per unit length of a phantom circuit than for a side circuit.

The contacts t_1 of relay T are normally in spacing position due to the current in the biasing winding, and move into marking position on the circuit being taken into use, the current sent over the junction overcoming the biasing current.

During the period whilst the incoming junction circuit is waiting for the arrival of the first impulse a part of the resistance connected in series with the biasing winding of relay T is short circuited so that the biasing current is increased. When the impulse is received therefore relay T moves its contacts into spacing position more quickly than would be the case if the normal biasing current alone were present and the first impulse is lengthened. During the first impulse the biasing current is restored to its normal value and on subsequent impulses relay T moves its contacts to spacing position under the influence of a lower biasing current than on the first impulse.

The two lines extending to the right hand side of the drawing are connected to the normal impulse receiving circuits of a selector switch, impulses being repeated thereto by contacts of relay HI whilst relays I and DI form a supervisory bridge. This is separated from relay T by a high pass filter consisting of condensers C_1 , C_2 , C_3 and C_4 of capacity 4 MH each in series in the line and inductance L of $\frac{1}{2}$ henry in shunt. This gives an attenuation of $\frac{3}{4}$ db. at 500 c. p. s. and $\frac{1}{2}$ db. at 900 c. p. s. This prevents surges which arise from the operation of the selector switch circuits from affecting the sensitive telegraph relay T, but does not substantially attenuate or distort speech currents.

The detailed operation of the circuit is as follows: When an operator inserts a plug into the jack on the left of the drawing relay S operates to battery on the sleeve of the jack and lights a supervisory lamp (not shown). Relay HS operates in series with the upper winding of relay A to earth in the operator's cord circuit, whilst relay DK operates in series with the lower winding of relay A to battery in the cord circuit. Relay A operates. At front contacts s_1 and a_1 a circuit is completed for relay SS which operates and at contacts ss_1 closes a locking circuit independently of contacts a_1 . At contacts ss_3 and

ss4 a loop including windings of relay D is extended over the junction J to the incoming repeater; relay D does not operate in series with the high resistance R3.

Relay T in the incoming repeater has its contacts *t1* normally biased to spacing. On completion of the loop the bias is overcome and its contacts *t1* move to marking position. Relays B and HI operate. Relay HI at contacts *hi1* connects relays I and DI in a loop across the selector circuit. Relay I operates and at contacts *ii1*, short circuits resistance R1 which is in series with the biasing winding of relay T and this increases the current flowing in the biasing winding. Relay DI cannot operate at this time because of the presence of rectifier MRA in series therewith and rectifier MRB shunting it.

When the operator throws the dialling key in her cord circuit battery is removed from the ring of the plug and accordingly relay DK releases. Relay DR then operates over ss2 front *dk1* back. At contacts *dr4*, relay HS is connected to the tip of the plug independently of relay A. At contacts *dr1* and *dr3* the outgoing junction is disconnected from the cord circuit, and battery and earth are connected to the respective wires thereof. At contacts *dr2* a short circuiting path for this battery and earth is prepared.

Relay HS releases in response to the first and subsequent circuit interruptions caused by the operator's dial and at contacts *hs1* short circuits battery and earth from the junction, removing current from the right hand winding of relay T in the incoming junction group. The bias current in the left hand winding of relay T takes control and contacts *t1* move to spacing. Relay HI releases and at contacts *hi1* repeats the impulse to the selector. On the first impulse relay C operates and at contacts *c1* places a short circuit across the relays I and DI. Relay I releases and at contacts *c2* and *ii1* the short circuit across resistance R1 is removed, again reducing the current in the left hand bias winding of relay T, so that relay T operates its contacts to marking position against a low biasing current. This arrangement ensures that the first impulse is not shorter than succeeding impulses.

At the end of the train of impulses relay C releases and removes the short circuit across relays I and DI and I again operates.

The operator restores the dial key, relay DK operates and DR releases reconnecting relay D and the cord circuit to the junction.

When the called subscriber takes his receiver from the hook the usual reversal of current to the line takes place and relay DI now operates. Contacts *di1* short circuit resistance R3 and relay D operates. At contacts *d1* the right hand high resistance winding of relay DK is short circuited and an answering supervisory relay connected to the ring of the plug operates. This extinguishes the supervisory lamp.

When the call is finished and the called subscriber places his receiver on the switchhook relay DI releases and at contacts *di1* inserts resistance R3 into the loop across the junction. Relay D releases and in turn the supervisory relay in the cord circuit releases and relights the supervisory lamp. The operator removes the plug and the circuit restores to normal condition.

What is claimed is:

1. Telephone system for setting up connec-

tions automatically by means of impulses over a junction line, including a first polarized telegraph relay for receiving said impulses, said relay being provided with an operating and a biasing winding, respectively, means for causing current to flow in said biasing winding, whereby direct current signalling can be employed over a relatively long line and means whereby the value of the biasing current will be varied by and in accordance with varying resistance in the line.

2. System according to claim 1, in which said means causing current flow in said biasing winding includes a source of potential and a variable resistance, the value of which resistance is adjusted in accordance with the resistance of the line over which the impulses are received, in order to render the response of similar relays connected to different junctions the same.

3. System according to claim 1, in which the circuit including said biasing winding includes in series therewith a resistance and means for short-circuiting a part of said resistance before said relay responds to the first of said impulses, the short circuit being automatically removed after the response of said relay to said first impulse, so as to cause said first impulse to be not shorter than succeeding impulses.

4. System according to claim 1, and including a further circuit extending from said junction and means for repeating impulses received by said first telegraph relay to said further circuit and also including a high pass filter separating said telegraph relay from said impulse repeating means, whereby voice signal currents can pass through said filter, but signal impulses are blocked thereat.

5. Telephone system for setting up connections automatically by means of impulses over a junction line, including a first polarized telegraph relay for receiving said impulses, said relay being provided with an operating and biasing winding, respectively, and also including a resistance connected in series with said operating winding of said telegraph relay in a loop across said junction, means for short-circuiting said resistance so as to send a backward supervisory signal, and a marginal relay at the outgoing end of said junction adapted to respond to said supervisory signal so that supervision is maintained over said junction and a subscriber sub-station connected thereto.

6. Telephone system for setting up connections automatically by means of impulses over a junction line, including a first polarized telegraph relay for receiving said impulses, said relay being provided with an operating and a biasing winding, respectively, means for causing current to flow in said biasing winding, and impulse transmitting equipment including means for alternately connecting battery and earth to the respective sides of the outgoing portion of said junction and short-circuiting said battery and earth from said junction, whereby said telegraph relay is operated by said impulses.

7. System according to claim 6, and also including means by which the battery and earth normally connected to the respective sides of said junction are short-circuited from said junction in response to an interruption derived from said impulse transmitting equipment.
